[57] ABSTRACT

A driving mechanism for a date-or-day indicator comprises a gear driven at the rate of n revolutions daily and carrying a pivotal lever adapted for meshing with a drive gear secured to the indicator. The lever is moved by a cam coaxial with the drive gear and located in the same plane of the lever and revolving at the rate of $(n + 1)$ revolutions daily in the same direction as the driven gear so that a nose of the cam causes the lever to enter once every 24 hours into the path of the drive gear to advance the indicator.

**DRIVE MECHANISM FOR AN INDICATOR OF THE DATE
OR THE DAYS OF THE WEEK**

BRIEF SUMMARY OF THE INVENTION

The invention relates to a driving mechanism for a day or date indicator of a timepiece.

A problem in driving date-or-day indicators is the need for the changeover to take place once each day in the shortest possible time.

To effect such quick changeover, the present invention contemplates a driving mechanism of a timepiece for an indicator indicating the day of the month or the days of the week.

According to the invention, the driving mechanism comprises a gear secured to the indicator to drive the same, a rotary member driven at the rate of n revolutions daily, an actuating lever pivotably connected to said rotary member and rotatable therewith, and cam means rotating at the rate of $n+1$ revolutions daily and engageable with said actuating lever to pivot the same once every 24 hours into a position in driving relation with said gear to cause the lever to advance the gear and the indicator therewith at the rate of speed of the rotary member.

Two such driving mechanisms can be paired so as to drive a day and a date indicator simultaneously.

BRIEF DESCRIPTION OF THE DRAWING

FIG. 1 is a plan view partly broken away showing one embodiment according to the invention;

FIG. 2 is a perspective view of a portion thereof; and

FIG. 3 is a section taken along line III-III of FIG. 2.

DETAILED DESCRIPTION

The drawing shows an embodiment of a date and a day indicator movement and first the day indicator movement will be described in detail.

The day indicator movement comprises a rotatable plate at the periphery of which are inscribed the days of the week. A gear 4 is secured to the plate 1 for common rotation therewith. The gear 4 is advanced once every 24 hours by an arm 3 of a lever 5 as will be explained later. The lever 5 is pivotably connected by a pin 6 to a gear 7 which is driven in rotation so as to make n revolutions daily.

Lever 5 is in abutment with a cam 8 coaxial with gear 7 and rigidly connected with a gear 10 driven in rotation at the rate of $n+1$ revolutions daily. The cam 8 and lever 5 lie in a common plane above gear 7. The passage of a nose 9 on cam 8 opposite lever 5 causes the arm 3 on lever 5 to engage the teeth of gear 4 as shown in FIG. 1 and to rotate the gear 4 in concert with the gear 7.

A resilient detent 11 holds the indicator plate 1 in position until the plate is driven by arm 3.

The gear 4 is driven by arm 3 to advance the plate and position the next day in the window shown in chain dotted outline in FIG. 1.

The drive of the gears 7 and 10 in the ratio of $n/(n+1)$ revolutions each day is obtained by a pair of gears 12 which are driven by the watch movement.

Because, the arm 3 drives the gear 4 at the rate of rotation of the gear 7, the gear 4 will be driven n times as fast as compared to a conventional arrangement in which the arm is driven at the rate of 1 revolution per day. Thus the day change will take place n times more quickly. In practice, it has been found preferable to select the order of magnitude of n as 8.

Reference will next be made to FIG. 3 which shows in greater detail the components of the drive for a toothed date indicator rim 2. This drive is mounted beneath gear 7, symmetrical to the drive described for plate 1. The advance of rim 2 is effected by arm 3' shown in FIGS. 1 and 2. The arm 3' is on a lever 5' (FIG. 3) identical to lever 5, but mounted on the lower face of gear 7, symmetrical to lever 5. The lever 5' is pivotably mounted on gear 7 on pin 6' symmetrical with pin 6.

The lever 5' is actuated by a cam 8' identical to cam 8, the cam 8' being mounted in the same plane as the lever 5' and

symmetrically with cam 8. Cam 8' is also rigidly connected to gear 10 and is driven at a rate of $n+1$ revolutions daily, so that the drive of the date indicator rim 2 takes place under the same conditions as that of the day indicator plate 1 and, in particular, at the same speed.

Cams 8 and 8' are each in the shape of a curvilinear triangle whose three sides are formed by three identical arcs. The cams are driven about respective axes which are offset from their centers of symmetry.

10 Levers 5 and 5' have a profile such that they are positively driven by the respective cams and therefore require no return spring.

Obviously a different profile requiring springs could also be employed.

15 It should be noted that rim 2 makes one revolution a month and that plate 1 carries two series of the seven days of the week and makes one half-revolution each week. Without such arrangement, the pitch of the teeth of gear 4 would become too large unless such wheel were of very small diameter.

20 From the above it is seen that the day and date indicators are advanced at a speed of n revolutions daily by carrying the actuator levers 3 and 3' on rotary gear 7 rotating at n revolutions daily and moving the levers into operative driving positions

25 with respect to their indicators once every 24 hours by means of the cams 8 and 8' which rotate about an axis common with the gear 7 at a speed of $n+1$ revolutions daily. By the above arrangement, the cams each make one revolution daily relative to the gear 7 thereby effecting movement of the 30 levers to operative position once every 24 hours.

What is claimed is:

1. A driving mechanism for a day or date indicator, said mechanism comprising a gear secured to the indicator to drive the same, a rotary member driven at the rate of n revolutions

35 daily, an actuating lever pivotably connected to said rotary member and rotatable therewith, and cam means rotating at the rate of $n+1$ revolutions daily and engageable with said actuating lever to pivot the same once every 24 hours into a position in driving relation with said gear to cause the lever to advance the gear and the indicator therewith at the rate of speed of the rotary member.

40 2. A driving mechanism as claimed in claim 1 wherein said cam means and said rotary member rotate around a common axis.

45 3. A driving mechanism as claimed in claim 2 wherein said cam means is located in the same plane as the actuating lever.

4. A driving mechanism as claimed in claim 3 wherein said actuating lever includes an arm which engages said gear, and said cam means comprises a cam having a nose which engages the lever to introduce the arm into engagement with said gear.

50 5. A driving mechanism as claimed in claim 4 wherein the cam and lever are shaped so that the lever is positively driven by the cam throughout 360° rotation of the cam.

6. A driving mechanism as claimed in claim 4 wherein n is 8.

7. A driving mechanism as claimed in claim 4 comprising a first gear driving said rotary member and a second gear coaxial with said first gear and of different diameter driving said cam.

60 8. A driving mechanism as claimed in claim 4 comprising a second indicator, one indicator for the day, the other for the date, and a second driving mechanism including an actuating lever and a cam symmetrically disposed with respect to said rotary member.

65 9. A driving mechanism as claimed in claim 8 comprising a common shaft for said rotary member and said cams, said shaft passing through said levers, the cam and actuating lever of one drive mechanism being disposed at one face of said rotary member, while the same and actuating lever of the other driving mechanism are disposed at the opposite face of the rotary member.

70 10. A driving mechanism as claimed in claim 9 wherein said arms of the two actuating levers are diametrically opposite one another, the gear secured to one indicator being an external gear and the gear secured to the other indicator being an

internal gear, one arm being engaged with the external gear while the other is engaged with the internal gear so that the arms drive said indicators simultaneously.

11. A driving mechanism as claimed in claim 10 wherein the indicator for the days of the week includes the seven days of the week repeated at least once at the periphery of the corresponding indicator.
